SPECTACLE FRAME

Harry Weissman, 4 Imperial Court,
Great Neck, N.Y. 11023

Filed July 22, 1969, Ser. No. 18,331

Term of patent 14 years

Int. Cl. D16—08

U.S. Cl. D57—1

Fig. 1

Fig. 2

Fig. 3

Fig. 4

FIG. 1 is a top plan view of a spectacle frame showing my new design.

FIG. 2 is a front elevational view of the same.

FIG. 3 is a side elevational view of the same.

FIG. 4 is a cross-sectional view of the bridge, the end pieces of the frame, and the temple.

I claim:

The ornamental design for a spectacle frame, as shown.
